UNITED STATES PATENT OFFICE.

ARNOLD F. KNOOP, OF PEOTONE, ILLINOIS.

RADIOSWITCH.

Application filed June 22, 1922. Serial No. 570,051.

My invention relates to new and useful improvements in radio switches, and has for its principal object the provision of an improved construction of this character which will be highly efficient in use and economical in manufacture.

Other objects will appear hereinafter.

The invention consists in the combination and arrangements of parts hereinafter described and claimed.

The invention will be best understood by reference to the accompanying drawings forming a part of this specification, and in which,

Fig. 1 is a front elevational view of a radio switch embodying the invention,

Fig. 2 is a vertical sectional detail view of the same taken substantially on line 2—2 of Fig. 1,

Fig. 3 is a rear elevational view of the same, and

Fig. 4 is a sectional detail view, of the same, taken substantially on line 4—4 of Fig. 2.

The preferred form of construction, as illustrated in the drawings, comprises a cylindrical member A having flanges 10 and 11 and a central web 12, all of which are made of non-conducting material. The cylindrical member A is mounted on a suitable panel

13 by any suitable means, which is in this instance by screw members 12', and carries on its flanges 11 a plurality of spaced tap posts 14 arranged circumferentially with respect thereto, the heads 15 of the posts 14 are preferably square or rectangular in shape. Each of the tap posts 14 is connected by means of a circuit wire 16 to a tuning coil 17 as shown in Fig. 3. Journalled

40 in the cylindrical casing A and projecting outwardly from the panel 13 is a shaft portion 16 carrying collars 17 and 18 which are fixed in the desired position by set screws 19.

45 This selective arrangement of the collars 17 and 18 is such that the shaft portion 16 can be adjusted longitudinally with respect to the cylindrical member A so as to afford means for shortening or lengthening the outwardly projecting portion of the shaft beyond the panel 13 or affording means for reversing the cylindrical member A if desired.

50 A connection between the shaft portion and the heads 15 of the tap posts 14 is made through the medium of a brush 20 having an inwardly turned lip 21 which is adapted to successively engage the heads 15 when the

shaft 16 is rotated, the width of said lip 21 being of an applicable width adapted to span the spaces between the heads 15 of the tap posts when the brush is moved to contact with the adjacent head. The brush 20 has an end fitting a recessed portion formed by bevelling outwardly the edges of a projection 22 as at 23 forming an integral part of the collar 18, as at 23.

The shaft 16 is also connected in circuit with a suitable ground wire 24 connected to the tap posts 25' as at 25 by a member 26 of conductive material which is connected to the tap post 25' as at 27. From the tap post 25' the member 26 passes through an opening 28 formed in the web 12 as shown in Fig. 3, and brought in contact with the shaft 16 which passes through an enlarged portion 27' formed integrally on the member 26. The member 26 is preferably of resilient material having a slit 28 cut in the enlarged portion 27' as illustrated in Fig. 4, this construction having the effect of a lock washer. The enlarged portion 27' of the member 26 is positioned between web 12 and the collar 17 and is constantly in contact with the collar, due to the resiliency of the enlarged portion 27' which causes the split portions 28' and 29' to spring laterally from each other.

The shaft 16 is manipulated through the medium of a knob 29 which is fixed thereto by means of a set screw 30'. The knob 29 carries a dial plate 31 having a beveled edge 32 bearing numerical markings which represents each one of the tap posts 14. In order to determine the position of the brush 20 a groove or indentation 32 is formed in the panel 13 and when one of the numerical markings is opposite or in alignment with the groove 30 it will indicate that the brush is in contact with the tap post of that respective numerical marking. While the dial as herein set forth is the preferred construction it is to be understood that any dial of any approved type will serve the purpose as well.

When the brush member 20 is in contact with the tap post 25' the device will be thrown out of operation due to the fact that the ground wire 24 is connected to this respective tap post.

The operation of my improved radio switch is obvious from the description herein set forth and it need be only mentioned that by the construction of a switch for the pur-

poses herein set forth the cost of manufacture will be economical and the switch will be of great advantage and utility in many respects.

5 While I have illustrated and described the preferred form of construction for carrying my invention into effect, this is capable of variation and modification without departing from the spirit of the invention. I, 10 therefore, do not wish to be limited to the precise details of construction set forth, but desire to avail myself of such variations and modifications as come within the scope of the appended claims.

15 Having described my invention, what I claim as new and desire to secure by Letters Patent is:

1. A radio switch including a non-conducting hollow cylinder having a partition intermitting its ends; a conducting shaft passing through said partition; a series of tap posts passing through said cylinder between one end thereof and said partition; contacts on said tap posts interiorly of the cylinder; a

conductor engaging said shaft, leading 25 through said partition and connected to one of said tap posts; and a conductor electrically connected to and movable with said shaft and adapted successively to engage the contacts during rotation of the shaft 30 substantially as described.

2. A radio switch including a non-conducting hollow cylinder; a non-conducting partition spaced from one end thereof to provide an open end; a conducting shaft 35 journaled in said partition and extending into said open end; a series of tap posts passing through said cylinder circumferentially with respect thereto and into said open end; contacts on said tap posts within 40 said open end; a conductor extending from the shaft through the said partition to one of the tap posts and a conductor carried by the shaft in said open end for engaging said contacts, substantially as described. 45

In testimony whereof I have signed my name to this specification.

ARNOLD F. KNOOP.
